UNITED STATES PATENT OFFICE

ROY M. WYRICK, OF LOUISVILLE, KENTUCKY, ASSIGNOR OF ONE-HALF TO LYNN VAN ARSDALE AND ONE-HALF TO MILTON E. WALDROP, BOTH OF LEXINGTON, KENTUCKY

SUBTERRANEAN ANTENNA

Application filed November 3, 1928. Serial No. 316,980.

This invention relates to antennæ for use with radio receiving apparatus and more particularly to the construction of a subterranean antenna.

5 An important object of the invention is to provide in a device of this character a construction such that the antenna proper is shielded and, at the same time, a construction provided preventing corrosion of the 10 antenna. It has long been known that subterranean antennæ have certain advantages over the ordinary type, the principal advantage noted being that such antennæ are considerably freer from interference resulting 15 from static discharges than the ordinary aerial. They are, however, subject to corrosion, particularly when the antenna is disposed in certain types of soils and in locations where changing temperatures cause a 20 tendency to sweating of the metal forming the antenna. An important object of this invention is to produce an antenna which may be employed in any subterranean location and which is fully and completely shielded and 25 yet is unaffected by changing conditions.

A still further object of the invention is to produce a device of this character which may be very readily and cheaply manufactured.

A still further object of the invention is 30 the provision of a device of this character which will act both as an antenna and ground.

These and other objects I attain by the construction shown in the accompanying drawing, wherein for the purpose of illustration is shown a preferred embodiment of my invention and wherein:—

Figure 1 is a vertical sectional view through a subterranean antenna constructed in accordance with my invention, the connections 40 to a receiving set being diagrammatically illustrated;

Figure 2 is a transverse sectional view on the line 2—2 of Figure 1.

Referring now more particularly to the 45 drawing, the numeral 10 generally designates

a cylindrical container having its opposite ends closed and its upper end provided with a central opening 11. Within this container is arranged a tube or collector 12 in the form of a metallic body preferably connected with the wall of the cylindrical container through a small condenser 13. A lead armored insulated wire 14 is directed through the opening 11 and electrically connected to the body 12, while the armor 15 thereof is soldered or otherwise secured to the upper wall of the casing about the edges of the opening to complete the seal thereof. This container is evacuated, being preferably provided with a check-valved outlet 16 to assist in its evacuation.

A complete subterranean antenna of this character may be constructed with an overall length of eighteen inches and need not be buried in the ground for any great depth, a shallow hole approximately two feet deep sufficing for its reception. The wire 14 is connected to the antenna receiving binding post of the receiving apparatus, while the shield or armor 15 of the cable may be connected to the ground receiving binding post of the receiving apparatus.

It has been found that by evacuating the container, sweating of the body 12 and consequent short-circuiting of this body to the cylindrical casing is eliminated, and it has been further found that the efficiency in reception is increased by this evacuation approximately twenty per cent. Receiving apparatus employing an antenna constructed in this manner have been found to be very free from interference and to be highly selective. In construction, the casing 10 is preferably formed of copper and the inner body 12 is preferably in the form of an aluminum cylinder.

The construction hereinbefore set forth being capable of a certain range of change and modification, I do not limit myself thereto except as hereinafter claimed.

I claim:—

A subterranean antenna comprising an evacuated metallic container, a collector within and space-insulated from the walls of the container, an insulated lead wire electrically connected to the collecting body and having insulated passage through the wall of the container, and a condenser connecting said container and collecting body.

10 In testimony whereof I hereunto affix my signature.

ROY M. WYRICK.
